UNITED STATES PATENT OFFICE.

FREDERICK L. FULLER, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,161,042.

Specification of Letters Patent.

Patented Nov. 23, 1915.

Application filed December 13, 1911. Serial No. 665,454.

To all whom it may concern:

Be it known that I, FREDERICK L. FULLER, a citizen of the United States, residing at Dayton, in the county of Montgomery and State of Ohio, have invented certain new and useful Improvements in Cash-Registers, of which I declare the following to be a full, clear, and exact description.

This invention relates to improvements in accounting machines and one of the objects thereof is to provide such a type of machine with a plurality of independent accumulators any one of which may be brought into coöperative relation with a set of actuators, these actuators also being adapted to coöperate with a grand accumulator, which accumulates the total of several of the independent accumulators.

Another object of this invention is to provide mechanism for disabling the grand accumulator when certain of the independent accumulators are brought into coöperative relation with the actuators.

Another object of this invention is to provide transfer devices which are common to the independent and the grand accumulators.

A further object of this invention is to provide an improved form of operating mechanism for the indicators whereby said indicators are moved directly from one position to another without returning to their normal starting position.

A further object of this invention is to provide a special bank of keys with suitable locking mechanism therefor, so constructed that when certain accumulators are in coöperative relation with the actuators, the key corresponding in designation to the selected accumulator will be unlocked, while when other accumulators are brought into coöperative relation with the actuators all of the said keys are unlocked so that any one of the same may be operated.

Another object of this invention is to provide a movable frame carrying record material upon which are entered written and printed data, the said frame being moved from one position to another to have the different data entered thereupon.

A still further object of this invention is to provide a check printing mechanism with an improved form of check ejector.

With these and incidental objects in view, the invention consists in certain novel features of construction and combinations of

parts, the essential elements of which are set forth in appended claims, and a preferred form of embodiment of which is hereinafter described with reference to the drawings which accompany and form part of the specification.

Figure 1 is a central transverse sectional view through a machine of the type shown in the Patent No. 580,378, granted to Cleal and Reinhard, April 13, 1897, with the improvements applied thereto. Fig. 2 is a detail view of a special indicator with the alining device therefor. Fig. 3 is an end elevation showing the multiple accumulator construction which is substantially identical with that disclosed in the application of E. J. Von Pein, Serial No. 342,887, filed November 10, 1906. Fig. 4 is a sectional view through the special key bank showing the interlocking mechanism between the accumulator selecting mechanism and the special keys. Fig. 5 is a sectional view taken just inside of the multiple accumulator frame and showing the accumulator selecting mechanism. Fig. 6 is a detail view of part of the operating devices for the special indicator. Fig. 7 is an enlarged sectional view through the frame carrying the multiple accumulators and the grand total accumulator, and also showing actuators and transfer devices which are common to the independent and grand accumulators. Fig. 8 is a detail view of a mechanism for disabling the grand accumulator when it is desired to enter a transaction upon one of the independent accumulators without entering it upon the grand accumulator. Fig. 9 is a partial sectional view through the machine showing the actuating mechanism for the tens of shillings indicator. Fig. 10 is a front elevation of the units and tens of shillings indicators. Fig. 11 is a detail view of the setting mechanism for the type carriers. Fig. 12 is a detail view of the special bank of keys and the locking devices therefor, which devices are controlled by the accumulator selecting mechanism. Fig. 13 is a perspective view of one of the locking devices shown in Fig. 12. Fig. 14 is an end elevation of the printing mechanism. Fig. 15 is an enlarged view partially in section of a portion of the printing mechanism. Fig. 16 is a top plan view of the printing table over which the record material passes. Fig. 17 is an enlarged view of the improved check ejector

and the operating cam therefor. Fig. 18 is an enlarged view of the cam and connections for operating the platen to take an impression from the type carrier. Fig. 19 is an enlarged view of the ribbon winding mechanism. Fig. 20 is an enlarged view of a portion of the check ejector shown in Fig. 17.

Described in general terms, the invention comprises a single series of actuators which are common to a plurality of independent accumulators and a grand accumulator, the independent accumulators being mounted upon a movable frame, and any one of them being arranged to be brought into co-operative relation with the actuators by a lever, which is adjustable to different positions. The grand accumulator is constructed to have entered thereupon by the actuators, the amounts accumulated upon several of the independent accumulators, with provisions for disabling the grand accumulator when certain others of the independent accumulators are brought into co-operative relation with the actuators. Transfer devices are mounted in juxtaposition to the actuators and are common to the independent and grand accumulators. A series of special keys is provided, bearing designations similar to several of the accumulators, with provisions for preventing the operation of any other key besides the one corresponding in designation to the accumulator that is in co-operative relation with the actuators. This preventing or locking mechanism is under the control of the adjustable lever and is so constructed that when certain of the accumulators are brought into co-operative relation with the actuators, by the movement of the adjustable lever, any one of these keys is free to be operated. An improved form of operating mechanism for one of the indicators is provided, which operating mechanism is capable of being differentially adjusted in one direction and then moved in another direction for directly positioning the indicator from one position to another.

The various improvements have been shown in a machine adapted to English currency. An improved form of operating device for the tens of shilling indicator and the tens of shilling accumulator actuator is provided, which actuating mechanism is, when necessary, moved one step under the control of the tens of shilling indicator, and is returned to normal position upon a succeeding operation of the machine.

A movable frame carrying an autographic strip is provided, upon which strip is entered written and printed records. The frame normally is in such position as to receive the written record, and, upon the operation of the machine, will be moved into position to receive an impression from a set of type carriers in alinement with the written record and afterward be restored to its normal po-

sition, by which restoration the autographic strip is fed. An impression is also arranged to be taken upon a check strip from the type carriers, which strip is then severed and the check ejected from the machine to be given to the purchaser as a receipt for the transaction.

For the purpose of illustration, these improvements have been shown in a machine of a type well known upon the market, which machine is adapted to the English monetary system, but it is to be understood that these improvements are not to be limited to this particular type of machine or to the particular monetary system shown, as they with equal facility may be used with other well known types of machines now upon the market, and which are adapted to take care of other monetary systems besides that herein shown.

The type of machine to which these improvements have been shown applied, as is well known, is provided with a series of banks of amount keys 1, each bank of which controls the differential movement of a segment 2 which is loosely mounted upon a rock shaft 3. Intermediate gears 4 loosely mounted upon a shaft 5, mesh with the segments 2 and also with gears 6 secured to amount indicators 7, from which it will be seen that any movement of the segments 2 under control of the keys 1, is imparted to the amount indicators 7.

In the aforementioned Von Pein application and in United States Patent No. 765,767, granted to Thomas Carroll on July 26, 1904, these intermediate gears 4 are secured to the inner end of nested sleeves, which sleeves at their outer ends are provided with yokes carrying segments for actuating the accumulators. With this sleeve construction, it is necessary to employ the yokes in order to bring the actuating segments for the different denominational elements of the accumulator into proper co-operative relation therewith. In the present construction, these sleeves and yokes are done away with and the movements of the intermediate gears 4 are transmitted through suitable pinions 8 to shafts 9, which shafts at their outer ends are provided with pinions 10 and 11, which through the proper intermeshing of said pinions, operate the accumulating and printing mechanisms located at the left and right hand side, respectively of the machine.

The pinions 10 drive actuators 12 (Fig. 7), which actuators are loosely mounted upon the shaft 5 and are arranged to operate with any one of a series of independent accumulators 13, which are mounted upon a frame 14, that is rotatable about a stub shaft 15 projecting from a slide 16 (Fig. 3). The inner wall of the frame 14 is provided with a pinion 17 (Fig. 5) with

which meshes a segmental rack plate 18 loosely mounted upon a rod 19 suitably supported in the machine frame. Attached to this segmental plate 18 is a smaller segmental rack plate 20 which meshes with a rack portion 21 of a lever 22 loosely mounted upon the rock shaft 3. Near its upper end the lever 22 is provided with parallel links 23 which support a slide 24, the latter having a block 25 secured thereto, the outer end of which is beveled and engages with notches 26 formed in a plate 27 secured to one of the side frames 28 of the machine. The extreme upper end of the slide 24 has an offset 29 with which one end of a lever 30 contacts, the said lever being formed in the shape of a bell crank and suitably pivoted to the main lever 22. From this it will be seen that the main lever 22 is normally latched in its adjusted position by the block 25 of the slide 24 entering one of the notches 26 of the plate 27. When it is desired to adjust the lever 22, the auxiliary lever 30 carried thereby is operated, which depresses slide 24 and withdraws the block 25 from the notch 26 thereby leaving the lever 22 free to be moved. Any movement of this lever will, through the segmental rack plates 20 and 18 and pinion 17, impart a corresponding rotary movement to the frame 14 to bring any one of the accumulators 13 into coöperative relation with the actuators 12. To prevent the operation of the machine while the lever 22 is being adjusted from one position to another, the block 25 secured to the slide 24 is provided with an offset which lies above the outer edge of a segmental plate 31 which is carried by connected links 32 suitably mounted upon the side frame 28. The upper one of the links 32 is secured to a rock shaft 33, which rock shaft carries a rearwardly extending arm 34 having an upturned portion 35 at its extreme rearward end. When the machine is at rest the portion 35 is arranged to pass into a notch 36 formed in a disk 37 secured to a shaft 38, which is given a complete rotation upon each operation of the machine. When the auxiliary lever 30 is operated previous to the movement of the main lever 22, the slide 24 will be lowered, carrying the block 25 out of its recess 26, by which movement the offset of the block 25 engages the upper edge of the plate 31 and moves said plate inwardly, which movement, through the upper link 32, will rock the shaft 33 carrying the projection 35 of arm 34 into the notch 36 of disk 37 thereby locking the machine from operation until the slide 24 and coöperating parts return to their normal positions. This return movement of the parts above described is accomplished by a spring 39, the ends of which are secured to the arm 34 and to the side frame 28. The above described operation of the adjustable manip-

ulative device 22 and connections is substantially identical with that shown in the aforementioned Von Pein application and for further description of same, reference may be had to said application. After the selected accumulator 13 has been positioned by the adjustable manipulative device 22, the frame 14 carrying said accumulator will be elevated by a cam disk 41 (Fig. 3) secured to the shaft 5, into a groove 40 of which projects a roller 42 extending from the slide 16 carrying the frame 14. The slide 16 is guided at its upper and lower ends by frame work 43 suitably attached to the side frame 28. The segmental plate 18, operated by the adjustable lever 22, is arranged to contact with bumper plungers 44 (Figs. 3 and 5) at the extreme movement thereof, so as to prevent any racking of the mechanism that would occur if positive stops were provided. A grand accumulator 45 (Fig. 7) is provided, which accumulates the combined total of several of the independent accumulators 13, this grand accumulator being also actuated by the actuators 12. The grand total accumulator 45 is normally disconnected from the actuators and is constructed to be connected thereto when entries are made in any of the independent accumulators, the grand total of which, is accumulated by the accumulator 45. When certain other of the accumulators carried by the frame 14 is brought into coöperative relation with the actuators 12, the mechanism for connecting the grand accumulator with said actuators will be disabled so that entries may be made upon certain of the accumulators without entering the same in the grand total accumulator.

A frame composed of side arms 46 supports the grand accumulator 45, which frame is pivotally mounted in the frame work 43. Connected to one of the side arms 46 of the grand accumulator frame is the upper end of a link 47 (Fig. 8), the lower end of said link being provided with a nose 48, which, when the grand accumulator is to be moved into engagement with the actuators 12, rests in a notch 49 formed in the side of a slide 50, which slide is suitably guided by the shafts 5 and 38. Projecting from the slide 50 is a roller 51 that extends into a cam groove 52 formed in a disk 53 secured to the shaft 38. The shape of the groove is such that as the shaft 38 is rotated, the slide 50 will be lowered which will lower the link 47 and thereby rock the accumulator frame so as to carry the grand accumulator into engagement with the actuators 12. The accumulator frame 14 carries nine accumulators 13, six of which are for the purpose of accumulating the totals of sales of as many clerks, while the three other accumulators carried by the frame 14 are for the purpose of accumulating the totals of spe-

cial transactions, such as "Charge", "Received on account" and "Paid out" made by the different clerks. The grand accumulator 45 accumulates the combined total of 5 the six clerk accumulators, and when a special transaction is entered in one of the special accumulators, the above described mechanism for throwing the grand accumulator into engagement w' h the actuators is disabled, so that said grand accumulator will 10 not accumulate the items entered in the special accumulators, and this disabling of the throwing mechanism for the grand accumulator is accomplished in the following manner.

The segmental plate 18, which positions the accumulator frame 14, and which is operated by the adjustable manipulative device 22, is provided with a cam slot 54 (Figs. 20 5 and 8) into which projects a roller 55 extending from a lever 56 secured to one end 25 of a rock shaft 57. This rock shaft at its other end has secured thereto a rearwardly extending arm 58 to which is connected the lower end of a slide 59, the extreme upper 30 end of said slide being provided with an inclined slot 60, into which a pin 61 projects from the link 47. The shape of the slot 54 formed in the segmental rack plate 18 is 35 such that, when any one of the six clerks' accumulators is in position to be operated by the actuators 12, the lever 56 will be held in the position shown in Fig. 8. In this position the nose 48 of the link 47 will be in 40 the recess 49 of the slide 50, so that upon the operation of the machine the accumulator 45 will be rocked into engagement with the actuators 12. When any one of the three special accumulators is brought into coöperative 45 relation with the actuators 12, the roller 55 will pass into the camming portion 62 of the slot 54 and rock said lever in a clockwise direction (Fig. 8) and, through the arm 58, elevate the slide 59 which slide, 50 through the inclined slot formed in the upper end thereof, will cam the link 47 in a rearward direction, thereby carrying the nose 48 of said link out of the recess 49 formed in the slide 50. In order to prevent 55 the accumulator 45 from accidentally dropping into engagement with the actuators 12 when the link 47 is disconnected from the slide 50, said link at its rearward end is provided with a forked portion 63 which straddles one of the shafts 9 as the nose 48 of said link is disengaged from the recess 49. The slide 59 is provided with an elongated slot 64 near its upper end through which the shaft 38 passes, said shaft acting as a guide 60 for the slide in its movement.

A novel form of transfer devices are provided, which devices are common to the independent accumulators and the grand accumulators. These devices carry combined 65 trip and transfer pawls, which are normally

out of operative relation with the accumulators, but are constructed to be brought into operative relation therewith previous to the actuation of the accumulators by the actuators so that in case a transfer is to take 70 place the pawls will be positioned to effect said transfer, while the operative relation between the accumulators and the transfer devices is established, the transfer being effected during the disestablishing of operative 75 relation between the accumulators and said transfer devices.

The transfer devices are in the form of segmental plates 65 which are loosely mounted upon the shaft 5 adjacent to the actuators 12. Each of these transfer plates or devices 65 has mounted thereon combined trip and transfer pawls 66, which pawls are arranged to coöperate with the selected independent accumulator and the grand 80 accumulator. Each of the transfer plates 65 is provided with a rack portion 67 with which meshes a rack 68 formed upon the upper end of an arm 69 loosely mounted upon a rod 70 suitably supported in the 85 frame work of the machine. Projecting from each of the arms 69 is a roller 71 which plays in a cam groove 72 formed in a disk 73 secured to the shaft 38. The shape of the groove 72 in the disk 73 is such that previous 90 to the actuation of the selected independent accumulator and the grand accumulator, the arm 69 is rocked counter clockwise (Fig. 7) thereby rocking the transfer plates 65 in a clockwise direction by which movement 95 trip noses 74 formed upon the pawls 66 are brought into the paths of movement of pins 75 projecting laterally from the wheels of the selected independent and grand accumulators. If any of the elements of either the 100 independent or the grand accumulator passes beyond the "nine" position, its pin 75 will engage with the nose 74 of the corresponding pawl 66 and rock said pawl in a counter clockwise direction, in which position it will 105 be held by a spring operated retaining pawl 76 engaging with one of the two notches 77 formed in the carrying pawl 66. These retaining pawls are mounted upon the transfer plates 65 and are held by springs 78 110 into engagement with one of the notches 77 of the carrying pawl so as to prevent accidental displacement of said pawl. As the pawl 66 is rocked by the pin 75 of the accumulating element contacting with the trip 115 nose 74, a carrying nose 79 projecting laterally from said pawl will be positioned to engage with a tooth of a gear 80 carried by the accumulating element of the next higher 120 denomination upon the actuation of said pawl. Upon the return to normal position of the transfer plate 65 carrying the pawl 66, the carrying nose 79 of said pawl will rotate the accumulating element of the next 125 higher denomination one step, it being un- 130

derstood that previous to this operation of the carrying pawl, the frames 14 and 46 carrying the independent and the grand accumulators will be moved by their respective cams so as to carry the said accumulators out of engagement with the actuators, so that the transfer can be effected without rotating the actuators 12. In the actuation of an accumulating element by its carrying pawl 66, the said pawl will be restored to its normal position relative to plate 65 by the rotation of the accumulating element with which it is in engagement, in which position it will be held by its retaining pawl 76. It will be noticed that this carrying operation takes place while the transfer devices are being moved out of operative relation with the accumulators. It is also to be understood that the cams 73, for actuating the arms 69 and the transfer plates 65, are arranged upon the shaft in such a manner that the transfer devices 65 are successively returned to normal position in order to effect a transfer required by a transfer as is well known in the art. Pins 81 projecting from the transfer devices 65 limit the movement of the combined trip and transfer pawls 66 as is plainly shown in Fig. 7.

The elements of the independent and the grand accumulators are frictionally held in their adjusted position by retaining pawls 82 which are spring pressed into engagement with the pinions 80 of the accumulating elements.

The next feature of this invention to be described relates to the locking mechanism for the special bank of clerks' keys. This mechanism is under the control of the adjustable manipulative device so that when any one of the clerk accumulators is brought into coöperative relation with the actuators by said manipulative device, the corresponding clerk's key will be released while the remaining keys will be locked from operation. When any of the special accumulators is brought into coöperative relation with the actuators by the adjustable manipulative device all of the special keys are released.

This special bank comprises six clerks' keys 83 (Figs. 5 and 12) corresponding in designation to the six clerks' accumulators mounted upon the movable frame 14. Pins 84 project from the clerks' keys 83 and engage with locking devices 85 pivotally mounted as at 86 upon one of the supporting frames 28 of the machine. These locking devices are so constructed as to permit the operation of only one key at a time, as fully shown in Fig. 12. Pins 87 project through elongated slots 88 of said locking devices into the side frame 28 so as to limit the movement of said devices. Each of the locking devices 85 has a lateral extension 89 (Figs. 4, 12 and 13), which projects through an opening 90 in the side frame 28.

The block 25 of the slide 24 carried by the adjustable manipulative device 22 coöperates in such a manner with the extensions 89 of the locking devices 85 that when said block is in any one of the six upper notches 70 of the plate 27, it so adjusts the two adjoining devices 85 as to permit the passage of the pin 84 of the clerk's key 83 corresponding to the position of the adjustable manipulative device, so that said key may 75 be operated, while the rest of the keys will be locked from operation by said locking devices 85. As there are no locking mechanism devices to coöperate with the block 25 when the adjustable device is moved to any 80 of its three lower positions, in which position the special accumulators carried by the movable frame are in coöperative relation with the actuators, any of the clerks' keys 83 may then be operated. 85

After one of the clerks' keys 83 has been depressed, it is impossible to adjust the manipulative device 22, thereby precluding the possibility of depressing a clerk's key and then moving the manipulative device to another position so as to bring a different accumulator from that corresponding to the key depressed into coöperative relation with the actuators. This is accomplished as follows. Upon the depressing of one of the clerks' keys 83 (Fig. 5) a detent 238 will be elevated and, through lug 239 projecting from said detent engaging with an arm 240 secured to a shaft 241, thereby rock said shaft in an anti-clockwise direction, as is well known in the art. This shaft has projecting therefrom an arm 246, which carries at its extreme rear end a stud 247 that normally rests upon a shoulder 248 of a lever 249, which lever is held in the position shown in Fig. 5 by a spring 250, the ends of which are connected to the arm 246 and to the lever 249. Upon the rocking of the shaft 241 by the depression of one of the clerks' keys, the lever 249 will be rocked in a clockwise 100 direction so as to carry a shoulder 257 formed upon the lower end thereof over a plate 252 formed upon the previously described arm 34 and thereby lock said arm 105 from movement, which consequently prevents the adjustment of the manipulative device 22. At the end of the operation of the machine the lever 249 is permitted to return to its normal position, shown in Fig. 5, by the stud 247 passing above the shoulder 110 248 of said lever. 115

From the above description it will be seen that a very simple and efficient locking mechanism is provided, which mechanism is under the control of the adjustable manipulative device when any one of the clerks' accumulators is in coöperative relation with the actuators, while the control of said locking devices is relinquished by the adjustable manipulative device when any one of the 125 130

special accumulators is brought into co-operative relation with the actuators.

A special indicator is provided for indicating different classes of transactions, such as "Cash," "Charge," "Received on account," and "Paid out," which indicator is located above the amount indicators and is constructed to be controlled by the adjustable manipulative device so that when any 5 of the clerks' accumulators is in co-operative relation with the actuators, the special indicator will display a character indicating "Cash", or when the manipulative device is moved to a position to bring one of the 10 special accumulators into position to be actuated, the said indicator will be adjusted upon the operation of the machine to display a character corresponding to the special accumulator that is in co-operative relation 15 with the actuators. A novel form of actuator for positioning the special indicator is herein shown, which actuator is differentially adjusted in one direction under the control of the adjustable manipulative device and subsequently moved in another direction to move the indicator directly from 20 one position to another.

The herein before described lever 56, which is actuated by the cam slot 54 formed 25 in the segmental rack plate 18 controlled by the adjustable lever 22, has secured at its rear end (Fig. 5) the lower end of an arm 91, the upper end of the latter being provided with an anti-friction roller 92. When 30 the clerks' accumulators are in co-operative relation with the actuators, the roller 55 of the lever 56 plays in the concentric portion of the cam slot 54 formed in the segmental plate 18 and consequently does not move the 35 arm 91. When the special accumulators are brought into co-operative relation with the actuators by the adjustment of the manipulative device 22 into one of its three lower 40 positions, the cam portion 62 of the slot 54 will position the lever 56 differentially and thereby correspondingly adjust the arm 91. Intermediate its ends the arm 91 is provided 45 with an elongated slot 93, through which projects a roller 94 extending from an arm 50 95 loosely mounted upon the rod 70. The roller 94 after passing through the slot 93 enters into a cam groove 96 (Fig. 6) formed in a disk 97 secured to the shaft 38. The shape of the cam groove 96 is such that 55 after the lever 91 has been properly positioned under the control of the adjustable manipulative device 22, the upper end of said lever carrying the roller 92 will be rocked rearwardly by the disk 97, by which 60 movement the said roller 92 will pass into the seat of a forked portion of a lever 98. The upper end of this lever 98 is provided with a segmental rack 99 which engages 65 with pinions 100 secured to the supporting

rods 101 of a special indicator 102. When 65 the adjustable manipulative device is moved from one clerk's position to another clerk's position, the lever 91 will not be moved and consequently when the said lever is rocked by the cam groove 96, the special indicator 70 will not be rotated. If the special manipulative device is moved from a clerk's position to a special transaction position, or from one special transaction position to another, the lever 91 will be raised or lowered 75 so that when said lever is rocked, as before described, the roller 92 will engage with one of the side walls of the forked portion of lever 98 and move said lever until the roller passes into the seat of the fork portion. 80 By this movement of the lever 98, it will be seen that the special indicator 102 will be rotated directly from one position to another without returning to a normal starting position. 85

The amount indicators 7 and the special indicator 102 are provided (Fig. 1) with flashes 103 and 104 respectively, which flashes are arranged to conceal the indicators during the operation of the machine and to 90 be withdrawn from concealing position at the very end of the operation. These flashes are connected by a link 105 so as to move together. One of the supporting arms 106 for the amount flashes 103 has projecting 95 downwardly therefrom a pitman 107, the lower end of which is provided with an elongated slot 108 through which the shaft 38 passes. Projecting from the lower end of the pitman 107 is a roller 109 which plays 100 in a cam groove 110 formed in a disk 111 secured to the shaft 38. The shape of the groove 110 is such that upon the beginning of the rotation of the shaft 38 the flashes 103 will be withdrawn to a position to conceal 105 the amount indicators 7 and through link 105 rotate the flashes 104 to conceal the special indicator 102. Near the end of the rotation of the shaft 38, the pitman 107 will be elevated so as to withdraw the flashes 103 110 and 104 from concealing position and thereby expose the amount and special indicators. 110

It is to be understood that any well known form of alining mechanism may be used for the purpose of alining the indicators and holding the same in their adjusted position between the operations of the machine, which alining devices are withdrawn upon the beginning of an operation, and restored to their alining position at the 115 end of the operation of the machine. As an illustration of such a construction, the link 105 has fastened thereto an arm 112 which, when the link is raised to withdraw the flashes 104 of the special indicator, will contact with one of the flat surfaces of the special indicator and thereby properly aline it 120 as shown in Fig. 2, it being understood that 125

the special indicator is held in its adjusted position by the roller 92 remaining in the seat of the fork portion of the lever 98 until the alining arm 112 engages the flat surface 5 of the special indicator 102, after which the roller 92 is withdrawn from the side of the fork portion of the lever 98 so that the arm 91 carrying the roller 92 may be adjusted by the operation of the manipulative device 22.

10 As previously stated, the machine to which the improvements have been shown as applied is adapted for the English monetary system and has a novel form of actuating mechanism for the ten shillings indicator 15 and for operating the ten shillings actuator for the accumulator. This mechanism is best shown in Fig. 9, and its construction is as follows. A single key 113 representing ten shillings is mounted in one of the intermediate frames 28 of the machine and is held in its outermost position by its spring 114. The shank of the key 113 is provided with a notch 115, which, when said key is depressed against the tension of its spring 25 114, is engaged by an offset 116 of a detent 20 slide 117 and latched in its depressed position, the detent slide being suitably mounted by screws 118, which pass through elongated slots 119 formed in said detent, into 25 a plate 120 carried by the intermediate frame 28. The detent 117 is held in its lowermost position by a spring 121^a. When the key 113 is depressed, the detent is elevated by the inner bevel portion of the key contacting with the lateral projection 116 and is held elevated until the notch 115 presents itself to the projection 116 of the detent 117, when said spring 121^a will draw the detent 30 downwardly to latch the key in its innermost position. Upon this movement of key 40 113 its inner end will contact with a plate 121 pivotally mounted upon the stationary plate 120 and rock said plate 121 against the tension of a spring 122, the ends of which 45 are connected to the plate 121 and to a link 123. This movement of the plate 121 will cause an arm 124 mounted upon said plate 50 to be rotated in an anti-clockwise direction against the tension of a spring 125 on account of a roller 126, which projects from the arm 124, contacting with the surface of a cam plate 127 secured to the rock shaft 3.

As is well known and fully disclosed in the aforementioned Cleal and Reinhard patent, the rock shaft 3 is first moved in a clockwise direction (Fig. 9) through about 90° and then returned slightly beyond its starting position and finally back to its normal position. The cam plate 127 secured to this 60 rock shaft 3 has a depression 128 in the upper surface thereof so that when the said plate is moved clockwise as shown in the figure, upon the beginning of the operation of the machine, the depression 128 will permit

the arm 124, carrying the roller 126, to be 65 rocked in a clockwise direction by its spring 125, this movement of the arm 124 being limited by a pin 129 projecting from the plate 121. Upon the return or anti-clockwise movement of the cam plate 127, the 70 roller 126 will be engaged by the forward wall of the depression 128 and will rock the arm 124 farther in a clockwise direction carrying the plate 121 therewith, owing to the 75 upper forward edge of the arm contacting with the pin 129 of the plate 121. This movement of the plate 121 caused by the arm 124, will, through the pin 129 contacting with the inner end of an elongated slot 130 formed in the previously mentioned link 80 123, move said link rearwardly against the tension of its spring 122. The rearward end of the link 123 is secured to an arm 131 loosely mounted upon the shaft 5 and extending downwardly therefrom. This arm 85 at its pivotal point has secured thereto a rearwardly extending arm 132 to which is secured one end of a link 133, the other end of which is secured to an arm 134 supporting the ten shillings indicator 135. From 90 this it will be seen that as the link 123 is moved rearwardly, the arms 131 and 132 will be rocked in a clockwise direction and through the link 133 rock the arm 134 in an anti-clockwise direction to bring the ten 95 shillings character on the indicator 135 into position to be exposed when the previously mentioned concealing means is withdrawn.

To avoid any confusion in the reading of the indication when the ten shillings key 100 is not depressed, the units of shillings indicator shown in Fig. 10 has that portion thereof where the zero would normally appear cut away so that if the ten shillings indicator is not operated, a blank space will 105 appear at the reading opening of the units and tens of shillings indicator. The ten shillings indicator 135 is of a smaller radius than the units of shillings indicator and a portion thereof plays within the units of 110 shillings indicator, this portion of the ten shillings indicator carrying the zero character. From this it will be seen that when the ten shillings indicator is operated independent of the units of shillings indicator, 115 the characters "1" and "0" will appear, the zero appearing through the opening formed in the units of shillings indicator. If the units of shillings indicator is operated in connection with the ten shillings indicator, 120 the zero of the ten shillings indicator will be concealed by the numeral displayed by the units of shillings indicator.

As previously stated, the rock shaft 3 is 125 returned beyond its normal position, by which movement a shoulder 136 formed upon the lower forward edge of the plate 127 contacts with the rearward extension

137 of the detent slide 117 and elevates said slide against the tension of spring 121^a, which elevation will release the ten shillings key, the latter being then returned to its 5 outermost position.

The arm 132 which is loosely mounted upon the shaft 5 has a segmental rack portion 138, which meshes with one of the pinions 8 and thereby rotates one of the shafts 10 9 to transmit the above described clockwise movement of the arm 132 through the pinions 10 to the actuator 12 for the tens of shillings elements of the independent and grand accumulators.

15 Upon the succeeding operation of the machine an extension 139 of the plate 127 will engage with a nose 140, projecting downwardly from the link 123, during the clockwise movement imparted to the plate 127, 20 and thereby restore said link and connections to normal position, as shown in Fig. 9.

A bell crank lever 141 is suitably mounted upon one of the intermediate frames 28 and the horizontal portion of the bell 25 crank is provided with a recess 142, into which projects a pin 143 secured to the detent slide 117. When this slide is elevated upon the depressing of a key, the bell crank 141 will be rocked in an anti-clockwise direction 30 and thereby carrying its vertical portion into the path of a plate 144 secured to the previously described plate 127, thus preventing the rocking of the shaft 3 and consequently the operation of the machine. 35 When the key is fully depressed, the detent 117 and the bell crank 141 will be restored to their normal positions by the spring 121^a. This plate 144 also prevents the operation of the key 118 while the machine is being 40 operated, by the surface of said plate passing in the path of the vertical arm of the bell crank 141.

The remaining features of the invention relate to the recording mechanism and comprise, first, a movable frame carrying a record strip, which frame is normally in position to have entered thereon written data, and upon the operation of the machine is moved to have an impression taken thereon 45 from a set of type carriers in juxtaposition to the written entry, after which the frame is returned to its normal position; second, an improved form of check ejector, which is provided with normally inoperative gripping means for the check, which gripping means is rendered operative upon taking an impression upon the check from the type carriers; and third, an improved form of feeding means for an inking ribbon, which 50 means is automatically reversed when the ribbon is nearly exhausted from either of the spools carrying the said ribbon. These different improvements relating to the printing mechanism will be described in the order 55 enumerated.

As previously stated, the shafts 9 (Fig. 1) are driven by the intermediate gears 4 through pinions 8, and these shafts at their right hand ends have secured thereto pinions 11 (Fig. 11) which pinions, through a 70 number of pinions mounted upon said shafts 9, transmit the movement of said shafts to segmental rack plates 145, which are loosely mounted upon the right hand end of the shaft 5. These rack plates 145 are provided with reduced rack portions 146 which mesh with racks 147 formed upon the upper end of levers 148 which are centrally pivoted upon the right hand side frame as at 75 149. The lower ends of the levers 148 are provided with rack portions 150 similar to the rack portions 147, which rack portions mesh with pinions 151 secured to the inner ends of nested sleeves 152, which at their outer ends carry type carriers 153. These 80 type carriers are thus under the control of the amount and the clerks' initial keys.

Upon the bringing of any one of the special accumulators such as "Charge", "Received on account" and "Paid out" 90 into co-operative relation with the actuators by the adjustable manipulative device 22, the lever 56 will be rocked by the cam portion 62 of the slot 54 formed in the segmental rack plates 18 (Figs. 5 and 8). This lever 56, 95 as previously stated, is secured to a shaft 57, which shaft extends through the machine and at its right hand end has secured thereto a rack plate 154, which meshes with one of the pinions 151 and through its sleeve 152 rotates the type carrier 153 bearing characters indicative of the special transactions, as said shaft 57 is rocked by the adjustment of the manipulative device 22 to bring the special accumulators into co-operative relation with the actuators.

A movable frame 155 (Figs. 14 and 15) is slidably mounted between guide strips 156, which are suitably secured to the frame work of the recording mechanism. This frame 110 155 supports a record strip storage and supply rollers 157 and 158, the strip being fed from the supply roller 157 around a table 159 and thence to the storage roller 158. The table 159 is pivotally mounted as 115 at 160 to an offset 161 of the sliding frame 155 and is limited in its downward movement by one of the side arms of the table 159 contacting with a stud 162 projecting from an offset 163 of the sliding frame 155. The storage roller 158 is provided with a 120 ratchet wheel 164, the teeth of which are arranged to engage with a stud 165 of a feed pawl 166, so as to feed the record strip when the frame is returned to its normal position. 125 This pawl 166 is drawn into a position such that its stud 165 will engage the ratchet teeth by a spring 167, the ends of which are secured to said pawl and to a bell crank lever 168 upon which the pawl is mounted. 130

This lever 168 is pivotally mounted as at 169 to the stationary frame work of the recording mechanism and has a horizontal member 170 which extends through an opening 171 in the covering 172 of the recording mechanism so as to be capable of manual operation when it is desired to feed the record strip without an operation of the machine. The lever 168 is held in the position shown in Figs. 14 and 15 by a coil spring 173, the ends of which are secured to said lever and to one of the guide strips 156 for the sliding frame 155. The movement of the manually operated lever 170 is limited by a stud 174 which passes through an elongated slot 175 formed in the lower end of said lever.

Projecting from about the center of the sliding frame 155 is a roller 176 which roller 20 plays in a recess 177 formed in the lower end of a lever 178, which is loosely mounted upon the hub of the operating crank handle 179. This lever 178 has projecting therefrom a roller 180 which plays in a cam 25 groove 181 formed in a disk 182 secured to a large intermediate gear 183. This gear is loosely mounted upon the stub shaft 149, which carries the crank levers 148 for adjusting the type carriers, as previously described. As the intermediate wheel 183 is given a half rotation only at each complete operation of the machine, the cam groove 181 is necessarily a duplex one, and the shape of the groove is such that upon the 30 half rotation of the gear 183, the lever 178 will be moved first in an anti-clockwise direction and then returned to its normal position. This movement of the lever will carry the slide 155 rearwardly so that a platen 40 roller 184 carried by the pivotally mounted frame 159 supported upon the slide 155, will be brought into position to take an impression from the type carriers 153. The side arms of the pivotally mounted frame 159, carrying the platen roller 184, have projecting downwardly therefrom extensions 185, which, when the sliding frame is moved rearwardly, are brought above plates 186 secured to an arm 187 of a vertically movable frame 188, so that when the extensions 185 in the pivotally mounted frame 159 are brought above the plates 186 and the frame 188 elevated, the platen roller 184 carried by the frame 159 will be moved to take an impression upon the record strip which passes 50 around said roller. The plates 186 are adjustably mounted upon the arms 187, so as to secure the proper pressure in order to obtain a good impression from the type carriers.

60 A portion of the covering for the recording mechanism is formed of transparent material 189, such as glass, so that the last few entries made upon the record strip are visible. This covering 189 is cut away as at 190 (Fig. 16) so that written data may be en-

tered upon the record strip in juxtaposition to where an impression will be subsequently taken upon the record strip from the type carriers, it being understood that the strip is of sufficient width to have both the written 70 and printed entries made thereon without interfering with each other.

The frame 188 which is moved vertically in order to carry the impression roller into contact with the type carriers 153, has projecting therefrom a screw stud 191, which plays in an elongated slot 193 formed in one member of a bell crank lever 194 (Figs. 14, 15 and 18) which lever is pivotally mounted upon the printer frame work as at 195. The 75 other member of the bell crank lever 194 is provided with a roller 196, which plays in a cam groove 197 in a disk 198 suitably secured to a gear 199, which makes a complete rotation at each operation of the machine. The 80 shape of the cam groove 197 is such as to rock the lever 194 twice during each rotation of the disk 198 so that the vertically movable frame 188 will be moved upwardly twice in order to take two impressions, the first upon 85 a check strip 200, which is severed and the check ejected, as hereinafter described, and the second upon the record strip carried by the movable frame.

The gear 199 is connected through intervening gearing 201 to the previously described intermediate gear 183 as is well known and fully shown in Fig. 14. The gearing from the operating handle 179 to the gear 199 is so proportioned that for 90 each two rotations of the operating handle 179, the gear 199 and the intervening gearing 201 will be given one complete rotation, while the large intermediate gear 183, as previously stated, will be given only a 95 half rotation.

A double set of feed rollers 202 and 203 (Fig. 14) are provided for feeding a portion of the check strip at each operation of the machine, into position to take an impression from the type carriers 153. This check strip passes through a stationary knife 204 supported by the frame work of the recording mechanism and over a movable knife 205 carried by the vertically movable frame 188, and thence over the platen roller 184 of the rocking table 159 carried by the sliding frame 155, it being understood that the pivotally mounted table is moved into position to take an impression 110 from the type carrier during the feeding of the check. As the check strip passes through the stationary knife on to the pivotally mounted table carried by the sliding frame 155, it will pass over an offset 115 206 of a lever 207 (Figs. 14, 15, 17 and 20) which is pivotally mounted as at 208 upon the frame work of the machine. This lever 207 has mounted thereon a pivotal arm 209, the forward end of which arm and the offset 120 130

206 forms means for gripping the check and ejecting it, after it has been severed by knives 204 and 205. The arm 209 is normally held in an inoperative position relative to the offset 206 by a trip pawl 210, which is also carried by the lever 207.

When the vertically movable frame 188 is first moved upwardly by the cam 198 an impression will be taken upon the check strip, as previously stated, and simultaneously with the taking of this impression upon the strip, it will be severed by the knife 205 which is carried by the movable frame 188. With the severing of the check, 15 the pawl 210 is tripped by a portion of the vertically movable frame coming into contact with a portion of the pawl which extends below the offset 206 of the lever 207. This tripping of the pawl 210 will release 20 the arm 209 and said arm will be rocked in an anti-clockwise direction (Fig. 17) by a spring 211 and thereby grip the check between it and the offset 206. The ends of 25 the spring 211 are connected to the lever 207 and the arm 209. Immediately after the taking of an impression upon the check and the gripping thereof by the arm 209 and the offset 206, the lever 207 carrying said arm and the offset will be rocked in a 30 clockwise direction by mechanism next described so as to carry the check forward of the platen roller 184. When the frame 159 carrying this platen roller is raised the second time, as previously described, an impression 35 will be taken upon the record strip in juxtaposition to the written entry already made thereon. This rocking of the lever 207 for the purpose of ejecting the check is brought about as follows. Near its pivotal point this lever is provided with a recess 212 in which plays a roller 213 projecting from the forward end of a lever 214, which is approximately centrally pivoted to the frame work of the recording mechanism, 40 and at its extreme rearward end is provided with a roller 215, which plays in a cam groove 216 in a disk 217 suitably secured to one of the gears comprising the intervening gearing 201 shown in Fig. 14. The timing 45 of the cam groove 216 relative to the cam groove 197 which operates the impression taking mechanism and the check severing devices, is such that the check ejector is operated immediately after the taking of 50 the first impression.

To restore the check gripping device, there is secured to the vertically movable sliding frame 188 a plate 218 (Figs. 15, 17 and 20) which plate is provided with a hook portion 219. When the check ejector is operated to deliver the check, a stud 220 projecting from the rearward end of the arm 209 passes below the hook portion 219 so that when the vertically movable frame is lowered after operating the means to take

an impression upon the check, the hook portion 219 will engage with the stud 220 and rock the arm 209 in a clockwise direction against the tension of a spring until said arm is latched by the pawl 210 in its normally inoperative position. The check when ejected passes through an opening 221 formed in the printer cabinet 222 and up the rearward bevel end of the glass covering 189 so that it may be grasped by the operator and handed to the customer as a receipt for the transaction.

An inking ribbon for the type is employed with provisions for feeding the ribbon from one spool to another, and, after one of the spools is nearly exhausted, automatically reversing the direction of feed of the ribbon.

The ribbon 223, as shown in Figs. 14 and 19, is fed from a roller 224 and guided by 85 suitable frame work 225, around the type carriers 153 and thence to a second roller 226. Each of the rollers 224 and 226 is provided with a ratchet 227, with which a double prong pawl 228 engages. This pawl 90 is pivotally mounted near the upper end of the vertical member of a bell crank lever 229, the horizontal member of said lever being equipped with a roller 230 which plays in a cam slot 231 formed in the previously 95 described lever 178. The double prong pawl 228 is provided with a fork portion in which plays a pin 232 projecting from an arm 233. A spring 234 connects the double prong pawl 228 and the arm 233. Each of 100 the rollers 224 and 226 is provided with a follower 235, which is held in engagement with its respective roller by a spring 236, the ends of which are connected to the followers 235.

Upon the reciprocation of the lever 178, as previously described, the bell crank 229 will first be rocked in a clockwise direction and then returned to its normal position. This movement of the bell crank will first 110 cause the double prong pawl 228 to be retracted over the ratchet 227 of the roller 226, and upon the return cause the double prong pawl to advance the spool 226. This operation will be continued until the ribbon on 115 the spool 224 is nearly exhausted, at which time the forward edge of the follower 235 co-operating with the ribbon on the spool 224 will pass in the path of the pin 232 projecting from the arm 233 carried by the bell 120 crank 229, and rock said arm in an anti-clockwise direction, which will cause the spring 234 connecting the arm and the double prong pawl 228 to pass to the opposite 125 side of the line joining the pivotal points of the double prong pawl 228 and the arm 233 from that shown in Fig. 19, and thereby cause the double prong pawl 228 to be rocked in a clockwise direction, withdrawing one of its prongs out of engagement with the 130

5 ratchet 227, on the spool 226, and causing the other prong to engage with the ratchet of the spool 224. Upon subsequent operations the ribbon will then be fed on to the spool 224 from the spool 226 until the latter spool becomes nearly exhausted, when the mechanism will be moved back to the position shown in Fig. 19 by the follower 235 which co-operates with the spool 226. The 10 pawl 228 is limited in its movement by the spring 234 by an offset 237 which plays in the fork portion formed in the extreme upper end of the bell crank 229.

15 The operating crank handle 179 is normally locked against operation and is only released by the operation of one of the clerk's keys 83. These keys (Fig. 5) as before stated, co-operate with detent 238 provided with a lug 239 which engages with 20 an arm 240 secured to a rock shaft 241. This shaft extends through the machine and has secured to the right hand end thereof (Fig. 14), a rearwardly extending arm 242 which is provided with a shoulder 243 at 25 its extreme rearward end, which shoulder plays in a recess 244 formed in a disk 245 secured to one of the gears of the previously mentioned gearing which intervenes between the gears 182 and 199. From this it will be 30 understood that upon the operation of any of the clerk's keys, its detent 238 will be elevated, and through the lug 239 and arm 240, rock the shaft in an anti-clockwise direction (Fig. 5) and in a clockwise direction (Fig. 35 14), which will withdraw the shoulder 243 out of the recess 244 thereby leaving the crank handle free to be operated. This locking construction is well known in the art.

40 While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

50 1. In an accounting machine, the combination with a movable frame and a series of independent accumulators mounted thereon, of a grand accumulator mounted independently of the frame carrying the series of accumulators, a set of actuators common to the grand and independent accumulators, means for moving the frame and selecting the independent accumulator to be actuated by the actuators, and a single series of devices having carrying pawls mounted thereon for effecting transfers in the selected independent accumulator and the grand accumulator.

60 2. In an accounting machine, the combination with a movable frame and a series of independent accumulators mounted thereon,

of a grand accumulator mounted independently of the frame carrying the series of accumulators, a set of actuators common to the grand and independent accumulators, means for moving the frame and selecting 70 the independent accumulator to be actuated by the actuators, means for moving the selected and grand accumulators into engagement with the actuators, a single series of devices having carrying pawls mounted 75 thereon for effecting transfers in the selected and grand accumulators, the said pawls being normally out of operative relation with the accumulators, and means for establishing and disestablishing operative relation 80 between the pawls and accumulators, the said pawls being constructed to effect transfers during the act of disestablishing operative relation between the pawls and the accumulators. 85

3. In an accounting machine, the combination with a plurality of independent accumulators for keeping a segregated analysis of transactions entered in the machine, of a grand accumulator for accumulating the 90 combined total of several of the independent accumulators, a set of actuators common to the independent and grand accumulators, means for selecting the independent accumulator to be actuated by the actuators, separate devices for engaging the selected and grand accumulators with said actuators, and means for disabling the devices for engaging the grand accumulator when certain of the independent accumulators with the actuators 100 are selected to be actuated by the actuators. 95

4. In an accounting machine, the combination with a plurality of independent accumulators for keeping a segregated analysis of transactions entered in the machine, of a 105 frame carrying said accumulators, a grand accumulator for accumulating the combined total of several of the independent accumulators, a set of actuators common to the independent and grand accumulators, an adjustable lever for moving the frame and selecting the independent accumulator to be actuated by the actuators, separate devices for engaging the selected and grand accumulators with said actuators, and means controlled by the adjustable lever for disabling the devices for engaging the grand accumulator when certain of the independent accumulators with the actuators are selected to be actuated by the actuators. 110 115

5. In an accounting machine, the combination with a plurality of independent accumulators for keeping a segregated analysis of transactions entered in the machine, a rotary frame carrying said accumulators, a 120 grand accumulator for accumulating the combined total of several of the independent accumulators, a set of actuators common to the independent and grand accumulators, an adjustable lever for rotating the frame and 125

selecting the independent accumulator to be actuated by the actuators, separate devices for moving the selected and grand accumulators into engagement with the actuators, and means controlled by the adjustable lever for disabling the devices for moving the grand accumulator into engagement with the actuators when certain of the independent accumulators are selected to be actuated by the actuators.

6. In an accounting machine, the combination with a plurality of independent accumulators for keeping a segregated analysis of transactions entered in the machine, a rotary frame carrying said accumulators, a grand accumulator for accumulating the combined total of several of the independent accumulators, a set of actuators common to the independent and grand accumulators, an adjustable lever and connections for rotating the frame and selecting the independent accumulator to be actuated by the actuators, separate devices for moving the selected and grand accumulators into engagement with the actuators, and means actuated by the lever connections for disabling the devices for moving the grand accumulator into engagement with the actuators when certain of the independent accumulators are selected to be actuated by the actuators.

7. In an accounting machine, the combination with means for entering different classes of transactions therein, of an adjustable device for determining the class of transaction to be entered in the machine, an accumulator for accumulating the total of transactions of a certain class, actuators for said accumulator, a slide having an invariable movement at each operation of the machine, a link normally connecting the accumulator and the invariably movable slide for the purpose of moving the accumulator into engagement with the actuators when transactions of a certain class are entered in the machine, and devices under the control of the adjustable lever for disconnecting the slide and link when transactions other than those to be accumulated are entered in the machine.

8. In an accounting machine, the combination with an indicator for indicating different classes of transactions, of a series of value indicators for indicating the amount of each transaction, means for operating said indicators, devices for concealing the indicators during the operation thereof, a link connecting said concealing devices, means for withdrawing the concealing devices after the indicators have been operated, and an arm projecting from the connecting link for alining the transaction indicator.

9. In an accounting machine, the combination with a digit carrier, of actuating mechanism therefor, an operating device for the latter mechanism normally out of operative

relation therewith, a depressible key, and a plate mounted independently of said actuating mechanism and controlled by the key so that upon the movement of the operating device the plate will be operated thereby to move the actuating mechanism for the digit carrier.

10. In an accounting machine, the combination with a plurality of accumulators, of actuators therefor, means for selecting the accumulator to be actuated by the actuators, operating mechanism for the actuators, means normally locking said operating mechanism, a series of keys controlling the locking means, and a series of stops actuated by the keys for preventing the simultaneous operation of a plurality of said keys, the said stops being controlled by the selecting means so that only the key corresponding to the selected accumulator can be operated.

11. In an accounting machine, the combination with a plurality of accumulators, of actuators therefor, an adjustable lever for selecting the accumulator to be actuated by the actuators, operating mechanism for the actuators, means normally locking said operating mechanism, a series of keys controlling the locking means, and a series of stops actuated by the keys for preventing the simultaneous operation of a plurality of said keys, the said stops being controlled by the adjustable lever so that only the key corresponding to the position of the lever can be operated.

12. In an accounting machine, the combination with a plurality of accumulators, of a movable supporting frame therefor, actuators for said accumulators, an adjustable lever for moving the frame and bringing one of the accumulators into position to be actuated by the actuators, operating mechanism for moving the selected accumulator into engagement with the actuators and then moving the latter to actuate the accumulator, means normally locking the operating mechanism, a series of keys controlling the locking means, and a series of stops actuated by the keys for preventing the simultaneous operation of a plurality of said keys, the said stops being controlled by the adjustable lever so that only the key corresponding to the position of the lever can be operated.

13. In an accounting machine, the combination with a manipulative device adjustable to a plurality of positions, of a series of keys one for each position of the manipulative device, and stops actuated by the keys for preventing the simultaneous operation of a plurality of said keys, the said stops being controlled by the manipulative device so that only the key corresponding to the position of the manipulative device can be operated.

14. In an accounting machine, the combi-

- nation with a manipulative device adjustable to a plurality of positions, of a series of keys, and key stops controlled by the manipulative device while in certain positions for permitting the operation of certain keys only, the said manipulative device while in other positions relinquishing the control of said stops so that any key of the series may be depressed. 5
- 10 15. In an accounting machine, the combination with a plurality of accumulators, of actuators therefor, means for selecting the accumulator to be actuated, a series of keys corresponding in designation to certain of the accumulators, and key stops controlled by the selecting means for preventing operation of a key different in designation than the selected accumulator, the said key stops being constructed to pass from under the control of the selecting means when accumulators other than those having corresponding keys are selected so that any key of the series may be operated. 20
- 15 25. In an accounting machine, the combination with a plurality of accumulators, of actuators therefor, a frame carrying said accumulators, an adjustable device for moving the frame and selecting the accumulator to be actuated, a series of keys corresponding in designation to certain of the accumulators, and key stops controlled by the adjustable device for preventing operation of a key different in designation than the selected accumulator, the said key stops being constructed to pass from under the control of the adjustable device when accumulators other than those having corresponding keys are selected so that any key of the series may be operated. 30
- 20 35. In an accounting machine, the combination with a movable frame carrying record material upon which printed and written records are arranged to be made, of type carriers for making the printed records, check issuing mechanism, and means for moving the record material frame from a position where the written records are made to a position to receive the printed records, and means whereby the said frame, while in this latter position, takes an impression from the type carriers upon the check. 40
- 25 45. In an accounting machine, the combination with a movable frame carrying record material upon which printed and written records are arranged to be made, of type carriers for making the printed records, means for moving the record material frame from a position where the written records are made to a position to receive the printed records, and a check severing mechanism constructed to take impressions from the type carriers upon the check and record material. 50
- 30 55. In an accounting machine, the combination with a movable frame carrying record material upon which printed and written records are arranged to be made, of a platen pivotally mounted in said frame over which the record material passes, type carriers for making the printed records, means for moving the record material frame from a position where the written records are made to a position to receive the printed records and then back to the first mentioned position, and a pawl for feeding the record material mounted independently of the movable frame and constructed to feed the record material upon the return movement of the frame. 60
- 35 40. In an accounting machine, the combination with a type carrier, of means for feeding a check strip thereto, means for severing the strip into checks, a normally inoperative device for ejecting the severed checks, and means controlled by the check severing mechanism for rendering the check ejecting device operative. 65
- 40 45. In an accounting machine, the combination with a movable arm for ejecting checks, of a normally inoperative device carried by said arm for gripping the checks, and means for rendering the gripping device operative. 70
- 45 50. In an accounting machine, the combination with a type carrier, of a platen, means for moving said platen for the purpose of taking an impression upon a check, and a normally inoperative device for ejecting the check, the said device being rendered operative by the platen moving means. 75
- 50 55. In an accounting machine, the combination with a type carrier, of a platen, means for moving said platen for the purpose of taking an impression upon a check from the type carrier, and a normally inoperative device for ejecting the check after an impression has been taken thereon, the said ejecting device being rendered operative upon the movement of the platen to take an impression upon the check from the type carrier and rendered inoperative again upon the movement of the platen away from the type carrier. 80
- 55 60. In an accounting machine, the combination with a type carrier, of a platen, means for moving said platen for the purpose of taking an impression upon a check from the type carrier, a device for ejecting the check after an impression has been taken thereon, a normally inoperative arm mounted on the ejecting device for gripping the check, and a pawl for holding the gripping arm in inoperative position, with connections from said platen moving means for disabling said pawl. 85
- 60 65. In an accounting machine, the combination with a movable frame carrying record material upon which correlated printed and written entries are made in juxtaposition to 90
- 65 70. In an accounting machine, the combination with a movable frame carrying record material upon which printed and written records are arranged to be made, of a platen pivotally mounted in said frame over which the record material passes, type carriers for making the printed records, means for moving the record material frame from a position where the written records are made to a position to receive the printed records and then back to the first mentioned position, and a pawl for feeding the record material mounted independently of the movable frame and constructed to feed the record material upon the return movement of the frame. 95
- 70 75. In an accounting machine, the combination with a type carrier, of a platen, means for moving said platen for the purpose of taking an impression upon a check from the type carrier, and a normally inoperative device for ejecting the check after an impression has been taken thereon, the said ejecting device being rendered operative upon the movement of the platen to take an impression upon the check from the type carrier and rendered inoperative again upon the movement of the platen away from the type carrier. 100
- 75 80. In an accounting machine, the combination with a type carrier, of a platen, means for moving said platen for the purpose of taking an impression upon a check from the type carrier, a device for ejecting the check after an impression has been taken thereon, a normally inoperative arm mounted on the ejecting device for gripping the check, and a pawl for holding the gripping arm in inoperative position, with connections from said platen moving means for disabling said pawl. 105
- 80 85. In an accounting machine, the combination with a type carrier, of a platen, means for moving said platen for the purpose of taking an impression upon a check from the type carrier, and a normally inoperative device for ejecting the check after an impression has been taken thereon, the said ejecting device being rendered operative upon the movement of the platen to take an impression upon the check from the type carrier and rendered inoperative again upon the movement of the platen away from the type carrier. 110
- 85 90. In an accounting machine, the combination with a type carrier, of a platen, means for moving said platen for the purpose of taking an impression upon a check from the type carrier, a device for ejecting the check after an impression has been taken thereon, a normally inoperative arm mounted on the ejecting device for gripping the check, and a pawl for holding the gripping arm in inoperative position, with connections from said platen moving means for disabling said pawl. 115
- 90 95. In an accounting machine, the combination with a type carrier, of a platen, means for moving said platen for the purpose of taking an impression upon a check from the type carrier, and a normally inoperative device for ejecting the check after an impression has been taken thereon, the said ejecting device being rendered operative upon the movement of the platen to take an impression upon the check from the type carrier and rendered inoperative again upon the movement of the platen away from the type carrier. 120
- 95 100. In an accounting machine, the combination with a type carrier, of a platen, means for moving said platen for the purpose of taking an impression upon a check from the type carrier, a device for ejecting the check after an impression has been taken thereon, a normally inoperative arm mounted on the ejecting device for gripping the check, and a pawl for holding the gripping arm in inoperative position, with connections from said platen moving means for disabling said pawl. 125
- 100 105. In an accounting machine, the combination with a type carrier, of a platen, means for moving said platen for the purpose of taking an impression upon a check from the type carrier, and a normally inoperative device for ejecting the check after an impression has been taken thereon, the said ejecting device being rendered operative upon the movement of the platen to take an impression upon the check from the type carrier and rendered inoperative again upon the movement of the platen away from the type carrier. 130

- each other while said frame is in different positions, of means for moving the frame from one position to another to receive upon the record material the correlated entries, type carriers for recording the printed entries, and means controlled by the movable frame for recording upon a check strip the printed entries recorded on the record material.
26. In an accounting machine, the combination with a movable frame carrying record material upon which correlated printed and written entries are made in juxtaposition to each other while said frame is in different positions, of means for moving the frame from one position to another to receive upon the record material the correlated entries, type carriers for recording the printed entries upon the record material, and a platen carried by the movable frame for taking an impression upon a check strip from the type carriers.
27. In an accounting machine, the combination with a movable frame carrying record material upon which correlated printed and written entries are made in juxtaposition to each other while said frame is in different positions, of means for moving the frame from one position to another to receive upon the record material the correlated entries, type carriers for recording the printed entries upon the record material, means controlled by the movable frame for recording upon a check strip the printed entries recorded on the record material, and means for severing the check strip into checks.
28. In an accounting machine, the combination with a set of type carriers, of means for differentially positioning said type carriers, a movable frame carrying record material upon which correlated printed and written entries are made in juxtaposition to each other while said frame is in different positions, means for moving the frame from one position to another to receive upon the record material the correlated entries, a check issuing mechanism, and a platen carried by the movable frame for taking impressions from the type carriers upon both the record material and check strip.
29. In an accounting machine, the combination with a set of type carriers, of means for differentially positioning said type carriers, a movable frame carrying record material upon which correlated printed and written entries are made in juxtaposition to each other while said frame is in different positions, means for moving the frame from one position to another to receive upon the record material the correlated entries, a check issuing mechanism, a platen carried by the movable frame, and means successively operating said platen for the purpose of taking first an impression from the type carriers upon the check strip and then upon the record material.

30. In an accounting machine, the combination with a plurality of independent accumulators, of a grand accumulator for accumulating the combined total of all items entered in several of the independent accumulators, a set of actuators, means for selecting any desired independent accumulator for actuation, separate means for engaging the selected accumulator and the grand accumulator with the actuators, and means controlled by the aforesaid selecting means for disabling the grand accumulator engaging means when certain independent accumulators are selected for actuation.

31. In an accounting machine, the combination with an adjustable frame, of a plurality of accumulators carried thereby, a grand accumulator for accumulating the total of all items entered in several of the independent accumulators, a set of actuators, means for adjusting the aforesaid frame to position any desired accumulator opposite the actuators, separate means for engaging the desired accumulator and the grand accumulator with the actuators, and means whereby the grand accumulator engaging means is disabled as an incident to the adjustment of the adjustable frame to position certain of the independent accumulators for actuation.

32. In an accounting machine, the combination with a plurality of accumulators, of a set of actuators, means for selectively establishing co-operative relation between any desired accumulator and the actuators, a grand accumulator for accumulating the total of all items entered in several of the independent accumulators and arranged to also be actuated by the aforesaid set of actuators, separate means for engaging the grand accumulator and the selected accumulator with the actuators, and means whereby the grand accumulator engaging means is disabled as an incident to the selection of certain of the independent totalizers.

33. In an accounting machine, the combination with a plurality of independent accumulators for keeping a segregated analysis of transactions entered in the machine, a movable frame carrying said accumulators, a grand accumulator for accumulating the combined total of several of the independent accumulators, a set of actuators common to the independent and grand accumulators, an adjustable lever for moving the frame and selecting the independent accumulator to be actuated by the actuators, separate devices for moving the selected and grand accumulators into engagement with the actuators, a cam positioned by means of the adjustable lever, and devices operated by said cam for controlling the engagement of the grand accumulator with the actuators.

34. In an accounting machine, the combination with a plurality of accumulators,

of actuators therefor, means for selecting the accumulator to be actuated, a type carrier arranged to print characters designating the accumulator actuated, a series of 5 keys under the control of which said type carrier is differentially positioned, a series of stops for the keys actuated by said keys, and means comprised by the aforesaid selecting means for controlling said stops, 10 thereby controlling the operation of the keys.

35. In an accounting machine, the combination with a plurality of accumulators, of actuators therefor, means for selecting 15 the accumulator to be actuated, driving mechanism for the actuators, means normally locking the driving mechanism, a type carrier arranged to print characters designating the accumulator actuated, means for 20 differentially positioning the type carrier, a set of keys for controlling said locking means and the means for positioning the type carrier, a set of stops actuated by the keys, and means comprised by the aforesaid 25 selecting means for controlling said stops, thereby controlling the operation of the keys.

36. In an accounting machine, the combination with a manipulative device adjustable 30 to a plurality of positions, of a series of keys, means actuated by the keys when the manipulative device is at certain of its positions to prevent simultaneous operation of a plurality of keys, and means whereby adjustment of the manipulative device to certain other positions will effect actuation of the first mentioned means to lock all but a 35 desired key against operation.

37. In an accounting machine, the combination with a manipulative device adjustable 40 to a plurality of positions, of a series of depressible keys, means actuated by depression of the keys when the manipulative device is at certain of its positions to prevent simultaneous depression of a plurality of keys, and 45

means whereby adjustment of the manipulative device to certain other positions will effect actuation of the first mentioned means to prevent depression of any but a desired key.

50

38. In an accounting machine, the combination with a movable frame carrying a record strip upon which printed and written records are to be made, of type carriers for making said printed records and printing 55 the same information upon a check, means for moving the record strip frame in and out of operative relation to the type carriers, means for feeding checks to the type carriers, means controlled by the record strip 60 frame for taking impressions on the checks, a normally ineffective device for ejecting checks, and means for rendering said ejecting device effective as an incident to printing the checks.

65

39. In an accounting machine, the combination with a type carrier, of a platen, means for operating the platen to take an impression on a check, an arm for ejecting the checks, a device carried by said arm for gripping checks, means normally latching said device in ineffective position, and means whereby operation of the platen will disable said latching means.

70

40. In an accounting machine, the combination with a type carrier, of a platen, means for operating the platen for the purpose of taking an impression on a check, an invariably moved arm for ejecting the checks, a device carried by said arm for gripping checks, means normally holding said device in ineffective position, and means whereby operation of the platen will disable said holding means.

75

In testimony whereof I affix my signature 80
in the presence of two witnesses.

FREDERICK L. FULLER.
